UNITED STATES PATENT OFFICE.

ADELARD DUMAS, OF WALHALLA, NORTH DAKOTA.

MATCH-BOX.

No. 916,922.

Specification of Letters Patent. Patented March 30, 1909.

Application filed June 4, 1908. Serial No. 436,659.

To all whom it may concern:

Be it known that I, ADELARD DUMAS, a citizen of the United States, residing at Walhalla, in the county of Pembina, State of North Dakota, have invented certain new and useful Improvements in Match-Boxes; and I do hereby declare the following to be a full, clear, and exact description of the invention, such as will enable others skilled in the art to which it appertains to make and use the same.

This invention relates to match boxes, of the class wherein the matches are dispensed one or more at a time as required, and has for one of its objects to simplify and improve the construction and increase the utility and efficiency of devices of this character.

Another object of the invention is to provide a simply constructed device which is permanently attached to the box in which the matches are sold and adapted to be readily arranged to enable one or more matches to be withdrawn, as required, to transform the closure in which the matches are sold into a match safe or dispensary.

With these and other objects in view the invention consists first in a distributing element attached to the cover or closure of the box and a receiving element attached to the box which may be so disposed as to coact to enable one or more matches only to be removed as required.

The invention further consists in a combined strike and distributor element attached to the cover or closure of the box and a receiving element attached to the body or receptacle portion of the box.

The invention further consists in a receptacle or body telescopically engaging with a closure or cover, and with a suspending means attached to the closure, and a distributor element also attached to the closure and a receiving element attached to the body or receptacle, and coacting to dispense one or more matches.

The invention further consists in a receptacle or body telescopically engaging with a closure or cover, and with a suspending means attached to the closure, and a distributor element also attached to the closure and a receiving element attached to the body or receptacle, the distributor element adapted to be extended over the receptacle to maintain it in position within the closure for transportation, and insertible into the

receptacle to dispense the matches as required.

With these and other objects in view the invention consists in certain novel features of construction as heretofore shown and described, and then specifically pointed out in the claims and in the drawings illustrating the preferred embodiment of the invention.

Figure 1 is a plan view of the improved device in closed position, or ready for shipment or transportation. Fig. 2 is a section on the line 2—2 of Fig. 1. Fig. 3 is an end view of the structure arranged as in Fig. 1. Fig. 4 is a front elevation of the improved device arranged for use, or in position to enable the matches to be removed therefrom. Fig. 5 is an end view from the bottom of the structure arranged as in Fig. 4. Fig. 6 is a section on the line 6—6 of Fig. 4.

The improved device is designed more particularly for use upon the ordinary telescopically arranged pasteboard match boxes in which matches are sold at retail, but may be employed upon boxes constructed of any suitable material, but for the purpose of illustration is shown applied to an ordinary match box in which the outer shell or closure is represented at 10 and the receptacle at 11.

Attached to the shell or closure 10 is a suspending eye or loop 12, foldable flat upon the receptacle 11, when not in use and by means of which the device may be suspended from a wall or other suitable structure when matches are to be dispensed therefrom.

Connected to the front face of the closure 10 at the opposite end to the loop 12 is a metal frame 13, having an abrasive surface 14, of emery or sand to form the "strike" surface and with a central finger recess 15, and with two wings or guards 16—17, extending from the frame 13, at each side of the opening 15, the wings being left in longitudinal alinement with the plane of the frame when first attached to the closure. Attached to the inner face of the adjacent end of the receptacle 11, is a metal plate 18, and with a central thumb aperture 19 and guards or stops 20—21 at each side of the aperture 19 and extending in alinement with the edges of the open side of the receptacle.

After the matches are deposited in the receptacle, a sheet of paper is disposed over the matches and the ends bent at right angles and forced between the mass of matches

and the ends of the receptacle, as shown at 22 in Fig. 2. The receptacle is then inserted into the closure and the wings 16—17, bent down over the adjacent end thereof and 5 the loop 12, bent down over the other end, the protecting paper strip 22 covering the apertures 15 and 19. The box is then ready for shipment or to be placed on the shelves for sale.

10 To arrange the device for use, the wings 16—17 are straightened to release the receptacle which is drawn out and the paper protecting strip 22 removed, and any matches which may have been displaced are 15 ranged in order so that they all lie at right angles to the longitudinal plane of the receptacle. The matches are then crowded toward the end opposite to the stops 20—21 so as to leave a cavity in the mass of matches 20 next the recessed end of the receptacle, so that when the receptacle is partly inserted into the receptacle, the wings 16—17 may be bent down into the cavity and against the matches, as shown in Fig. 6. The receptacle 11 is forced into the closure 10 until the 25 free ends of wings 16—17, are spaced the requisite distance from the plate 18, to permit one or more of the matches only to pass between them. If one match at a time is to be removed the distance between the wings and plates will be relatively close, but if two or more matches at a time are to be removed the receptacle will be drawn out slightly, and it is obvious that the number of matches 30 which are to be removed at each operation may thus be easily controlled. The loop 12, is then straightened out and the device suspended from a hook or nail in a convenient locality, the friction between the casing and closure being sufficient to maintain them in 35 position. When a match is required the

thumb is thrust through the aperture 19, and the fore finger through the aperture 15, and the lowermost match or matches as the case may be grasped and removed.

What is claimed is:—

1. In a device of the class described, a receptacle for the matches open at one side and having a recess in one end communicating with the open side, inwardly directed stop wings at the sides of the recesses, a closure 50 slidable over the receptacle and provided with a recess in one end opposite the recess of the receptacle, a bendable retarding device extending from the slidable closure, said retarders adapted to be bent over the outer surface of the receptacle when said receptacle is in closed position or inclined inwardly and spaced from the stop wings when the receptacle is in projected position.

2. In a device of the class described, a receptacle for the matches open at one side and having a recess in one end communicating with the open side, inwardly directed stop wings at the sides of the recess, a closure 65 slidable over the receptacle and provided with a recess in one end opposite the recess of the receptacle, a plate bearing upon said closure and provided with a recess registering with the recess of the same, said plate 70 having bendable projections at the sides of the recess thereof adapted to be bent over the outer surface of the receptacle when said receptacle is in closed position or inclined inwardly and spaced from the stop wings when 75 the receptacle is in projected position.

In testimony whereof, I affix my signature, in presence of two witnesses.

ADELARD DUMAS.
